UNITED STATES PATENT OFFICE.

WALTER P. TEN EYCK, OF WESTFIELD, NEW JERSEY, ASSIGNOR TO SNYDER & BLACK,
INCORPORATED, OF NEW YORK, N. Y., A CORPORATION OF NEW YORK.

DISPLAY CARTON.

Application filed January 29, 1921. Serial No. 440,963.

To all whom it may concern:

Be it known that I, WALTER P. TEN EYCK, a citizen of the United States, and a resident of Westfield, in the county of 5 Union and State of New Jersey, have invented certain new and useful Improvements in Display Cartons, of which the following is a specification.

This invention relates to display cartons 10 of that class, the blanks for which are die-cut from sheets of card-board and folded along die-impressed score lines, and adapted for containing merchandise and for being opened up to display a portion of the carton and 15 its contents. The object of my improvements is to provide an article of the class specified, the blank for which may be completed in one operation of stamping, which is adapted for receiving any printed matter 20 all upon one face of the blank, and which blank may be readily folded into receiving condition for merchandise, may be readily and securely closed for shipment and readily opened up and erected into display form.

25 With these ends in view and others which will appear hereinafter, my improved article comprises features which are illustrated in their preferred embodiment in the drawings accompanying this specification, where- 30 in:

Figure 1 is a plan view of the blank from which my improved carton is folded. Fig. 2 is a perspective view showing the carton partly folded. Fig. 3 is a perspective view 35 of the carton fully erected in display condition. Fig. 4 is a fragmentary perspective view illustrating the assembling of a portion of the carton. Fig. 5 is a lengthwise cross-sectional elevation of the carton cor- 40 responding with the assembled view of Fig. 3. Fig. 6 is a fragmentary perspective view 45 of the underside of the carton showing the erection of the easel member of the device. Fig. 7 is a view similar to that of Fig. 6 and showing a modification of what is shown in Fig. 6. The scale of Figs. 1 to 4 inclusive is equal, the scale of Figs. 5 to 7 inclusive is equal and about twice that of the earlier figures.

50 The blank, shown laid flat in Fig. 1, from which my improved carton is formed, has several features of advantage and economy, such as, minimum waste in cutting from the sheet, the outline of the blank being such 55 as to permit the cutting of successive blanks

in part from portions normally wasted; also the blank is unitary and suitable for forming the resultant carton without the addition of any loose pieces and entirely without gum or other extraneous fastenings; said 60 blank also has provision for reinforcing several walls of the carton by duplex thickness of wall, thereby permitting a minimum thickness of stock from which to cut the blank; furthermore, both when the carton 65 is assembled and closed in shipping condition and when erected for display, all exposed faces of the several walls are from one and the same face of the blank, which permits the use of "one face" stock and 70 enables the printer to embellish the carton with legends and decorations by printing on one side of the stock only. Also the body support, for use when displaying the contents of the carton, is formed from the body 75 portion of the blank and another portion of the blank provides a false bottom to cover the hole left by the outward folding of said support.

Directing attention now more particularly 80 to the drawings, in the following description and claims all references to "width" will be read vertically relatively to Fig. 1, and all 85 references to "length" will be read transversely relatively to that figure. My im- 90 proved blank, Fig. 1, comprises a plurality of attached members preferably demarcated from one another by score lines and along some edges of some of said members by cut- through separating lines. Body-bottom 2 95 is bounded widthwise by score lines 3 and 4, and lengthwise by score lines 5 and 6. Adjoining said bottom, at line 4, is body-side 7 extending widthwise the blank from score line 4 to similar parallel line 8. Said side 95 is of duplex character, comprising portions 7^a and 7^b divided by score line 9 running lengthwise midway between lines 4 and 8 and parallel therewith. Extending width- 100 wise from said side 7, is wing 10 of substan- 105 tially equal length with side 7 and bottom 2 and having a width substantially equal to the width of said bottom. Adjoining bottom 2 at its upper edge 3, is opposite duplex body-side 11 of substantially the same 110 character and dimensions as side 7. Wing 12 of side 11, while of substantially equal length with side 11, is relatively narrow, for purposes which will appear later herein. Body-end 13 is also of duplex character, 110

comprising equal portions 13^a and 13^b, divided by score line 14 running crosswise between lines 6 and 15 and parallel therewith. Said end 13 has a length equal to the width 5 of side 7, and a width equal to the width of bottom 2. Extending lengthwise from said end 13 is relatively short wing 16, preferably of a length similar to the width of wing 12 and of a width not more than that 10 of end 13. Extending widthwise in either direction from that half portion of end 13 lying next bottom 2, are tabs 17 and 18, each having a length slightly less than half the length of end 13 and each having a width 15 about equal to half the width of body 2. Single body-end 19 is located opposite end 13 relatively to body 2 and has a length from line 5 to line 20 equal to one half the length of end 13. Said end 19 is provided with opposite tabs 21 and 22, similar to and similarly located as tabs 17 and 18 of end 13.

That portion of the blank of Fig. 1 already described, ending at line 20, is sufficient for folding into a coverless carton of 25 practical utility and, if end 19 is made duplex and provided with lengthwise tab, all similar to end 13, a still more efficient container is provided.

However, in most cases, it is preferable to 30 provide said container with a cover 23. This cover extends lengthwise from the outer edge 20 of end 19 a distance substantially equal to the length of the body-bottom and said cover has a width equal to the 35 width of body-end 19. Said cover may be provided with opposite tabs 24 and 25 extending widthwise therefrom, each of said tabs having a width substantially half the width of one of the body-sides, as 11. The 40 length of each of said tabs is preferably somewhat less than the length of said cover. In some cases it is preferable to divide said tabs 24 and 25 midway their length, respectively, into two contiguous tabs on each 45 cover edge, as 24^a and 24^b on the upper edge and 25^a and 25^b on the lower edge, for purposes which will presently appear. In some cases cover 23 is provided with portion 26, extending lengthwise from boundary line 27 50 of said cover, a distance equal to the length of single body-end 19, said extending portion being provided with opposite tabs 28 and 29 extending widthwise therefrom. Said tabs are preferably of a width slightly 55 less than the width of tabs 24 or 25 and may have their outer corners 28^a and 29^a rounded off for purposes which will appear later herein.

The separating of tabs 24 and 25 into two 60 tabs each is useful in connection with a display feature of cover 23 which is as follows: In reaching from the widthwise edges of said cover 23 about midway the length thereof and lying between tabs 24^a, 24^b and 65 25^a and 25^b, are score lines 30, 31, respec-

tively. Said lines terminate at the opposite roots of a cut-through line 32 of some pleasing contour, herein illustrated as approximately a semicircle, in reaching toward single-body-end 19, whereby is formed a 70 semi-disc-like member 23^a. In some cases it is desirable to break line 32 at its mid-portion, thereby leaving member 23^a connected with its adjacent cover portion by a short portion 33. Said score lines 30, 31 being 75 connected with cut-through line 32, form a widthwise folding line for said cover about midway its length. For engagement with tabs 28 and 29, when the carton is erected in display position, opposite lengthwise slots 80 34, 35, midway widthwise sides 7 and 11, respectively, are provided. Each of said slots has a length slightly greater than the length of the respective tab with which it is engaged, and said slots are located near 85 end 19.

For supporting the carton when assembled in inclined display position, Figs. 3 and 5, body-bottom 2 has formed therefrom by cut-through lines and connected therewith 90 along widthwise score line 36 near end 19, lengthwise member 37 adapted for folding into a body support. Said member 37 comprises a plurality of lengthwise panels, as 37^a, 37^b, 37^c and 37^d, and is temporarily 95 retained in place by unsevered portions 41, 42 and 43. Each of said panels has a width preferably somewhat less than the width of bottom 2, so as not to weaken said bottom unduly, and each panel has a length approximately equal to the height it is desired 100 to raise that end of the assembled carton under which said body support is erected. In practice, panel 37^c is made somewhat longer than panel 37^a, for purposes which 105 will presently appear. Cut widthwise through bottom 2, between and parallel with score line 36 and end 19, is slot 38, panel 37^a being adapted for engagement with said slot when the member 37 is folded into supporting position. Also panel 37^d is preferably slightly longer than the distance between slot 38 and edge 5 of body-end 19, so that when said member 37 is folded into 110 supporting position the free end of panel 37^d will abut against end 19, thereby relieving the edge of slot 38 of strain. When member 37 comprises four panels, as shown in Fig. 1, panel 37^b, next to panel 37^a which is hinged along line 36 to the box bottom 2, 115 may be provided with opposite wings 39 and 40 extending from the sides thereof, respectively, each of said wings being of a contour 120 adapted for filling the quadrangular space formed at each side when said member 37 is folded, as shown in Figs. 5 and 6.

Directing attention now particularly to those figures succeeding Fig. 1, the blank of Fig. 1 is folded as follows: Ends 13 and 19 are folded upwardly at right angles to 130

bottom 2, tabs 17, 18, 21 and 22 are folded inwardly along lines 3 and 4, respectively, and portion 13^b is folded inwardly down against portion 13^a, wing 16 lying against the contiguous portion of bottom 2. Then side 11 is folded upwardly at right angles to bottom 2 against tabs 17 and 21 and portion 11^b is folded inwardly down over said tabs, wing 12 lying against bottom 2. Then side 7 is folded upwardly at right angles to bottom 2 against tabs 18 and 22 and portion 7^b is folded inwardly down over said tabs, wide wing 10 overlying narrow wings 12 and 16 and lying close against bottom 2 and 15 forming a lining therefor.

Cover 23 may then be closed over the erected box portion of the carton, Fig. 4, side tabs 24 and 25 being tucked within the box body against sides 11 and 7, respectively, 20 said tabs preferably having their widthwise free edges seated against wing 10 in the bottom of the box, whereby the cover is sustained against being pushed too far into the box. For securing and locking the cover in place onto the box portion, opposite tabs 28 and 29 of cover portion 26, are tucked in, respectively, between side portions 11^a and 11^b against tab 17, and side portions 7^a and 7^b against tab 18, cover portion 26 being folded downwardly against end 13, Fig. 4. Rounded corners 28^a and 29^a permit the free tucking in of tabs 28, 29, respectively.

For supporting one end of the carton for display purposes, member 37 is broken away at 41, 42 and 43 from bottom 2, is bent downwardly, successively, along the score lines between portions 37^c, 37^b and 37^a, 37^c, and along score line 36, then portion 37^c is tucked into slot 38 and pushed between bottom 2 and wing 10 against wall 19. The excess length of panel 37^c over that of panel 37^a permits panel 37^b to lie flat against base line 44 on which the front corner of the carton rests. Then outstanding wings 39 and 40 are folded inwardly at right angles to portion 37^b, filling the quadrangular space bounded by portions 37^a, 37^b, 37^c and the adjacent portion of bottom 2, thereby bracing said support in an efficient manner and locking portion 37^c in place.

For erecting cover 23 in display position, cover portion 26 is lifted away from end 18, thereby withdrawing tabs 28, 29 and the cover is lifted. The free end of said cover 55 is then bent forwardly and downwardly along lines 30, 31, attaching portion 33 being broken, whereby cover member 23^a is freed. Cover tabs 24^a, 24^b and 25^a, 25^b are at the same time folded inwardly against said cover 60 and said cover is folded to the position of Fig. 3, tabs 28, 29 being inserted in slots 34, 35 respectively thereby securely holding the cover in erected position.

In some cases it is desirable to employ a 65 simpler support than that shown in Figs. 5

and 6 for instance, in which case panel 37^c and wings 39 and 40 of member 37 may be omitted, panels 37^a and 37^b being formed contiguous and joined as shown in Fig. 7. This provides a U shaped support without 70 end braces.

I claim:

1. A carton including in combination a box-like structure having a bottom, said bottom having formed therefrom by cut- 75 through lines and connected thereto along a width-wise score line near one end a length-wise member adapted for folding into a body support, said member comprising a plurality of lengthwise panels, and a slot 80 widthwise said bottom between said end and said score line, that panel at the free end of said support member being adapted for engagement with said slot, said panel at the free end of said support member having 85 a length slightly greater than the distance between said slot and said contiguous end.

2. A carton including in combination a box-like structure having a bottom, said bottom having formed therefrom by cut- 90 through lines and connected thereto along a width-wise score line near one end a length-wise member adapted for folding into a body support, said member comprising four lengthwise panels, the panel next to that 95 panel portion which is connected to the bottom having a wing extending from either edge thereof, a slot widthwise said bottom, between said end and said score line, that panel at the free end of said support member being adapted for engagement with said slot, and means for locking said body support in erected position.

3. A carton including in combination a box-like structure having a bottom, said bottom having formed therefrom by cut- 105 through lines and connected thereto along a width-wise score line near one end a length-wise member adapted for folding into a body support, said member comprising 110 four lengthwise panels, the panel next to that panel portion which is connected to the bottom having a wing extending from either edge thereof, and a slot widthwise said bottom between said end and said score line, 115 that panel at the free end of said support member being adapted for engagement with said slot, said wings being adapted for locking said free end panel in place in said slot.

4. A carton including in combination a 120 box-like structure having a bottom, said bottom having formed therefrom by cut- through lines and connected thereto along a width-wise score line near one end a length-wise member adapted for folding into 125 a body support, said member comprising four lengthwise panels, the panel next to that panel portion which is connected to the bottom having a wing extending from either edge thereof, and a slot widthwise said bot- 130

tom between said end and said score line, that panel at the free end of said support member being adapted for engagement with said slot, said wings being adapted for locking said body support in erected position.

5. A blank for a folding carton including in combination, a body-bottom, opposite body-ends and opposite body-sides, one of said body-sides being provided with a wing 10 adapted for folding into the carton for forming a bottom lining, said body-bottom having formed therefrom by cut-through lines and connected thereto along a widthwise score line near one body-end a lengthwise member adapted for folding into a body-support, said member comprising four lengthwise panels, the panel next to that 15 panel portion which is connected to the body-bottom having a wing extending from either edge thereof, and a slot widthwise said bottom between said body-end and said score line, that panel at the free end of said support member being adapted for engagement with said slot, said wings being adapt-

ed for locking said body support in erected 25 position.

6. A carton including in combination a box-like structure having a bottom, said bottom having formed therefrom by cut-through lines and connected thereto along a widthwise score line near one end a lengthwise member adapted for folding into a body support, said member comprising four lengthwise panels, the panel next to that panel portion which is connected to the bottom having a wing extending from either edge thereof, and a slot widthwise said bottom, between said end and said score line, that panel at the free end of said support member being adapted for engagement with 35 said slot and said wings being adapted for folding into the quadrangular space bounded by three of the member panels and the bottom.

In witness whereof, I hereby affix my signature this 28th day of January, 1921.

WALTER P. TEN EYCK.
